UNITED STATES PATENT OFFICE.

HUGH M. ADAMS, OF WASHINGTON, DISTRICT OF COLUMBIA.

PORTABLE STORM-FRONT FOR STREET-RAILWAY CARS.

SPECIFICATION forming part of Letters Patent No. 773,620, dated November 1, 1904.

Application filed August 26, 1904. Serial No. 222,329. (No model.)

To all whom it may concern:

Be it known that I, HUGH M. ADAMS, a citizen of the United States, residing at Washington, in the District of Columbia, have invented certain new and useful Improvements in Portable Storm-Fronts for Street-Railway Cars; and I do hereby declare the following to be a full, clear, and exact description of the invention, such as will enable others skilled in the art to which it appertains to make and use the same.

This invention relates to improvements in portable storm-fronts for street-railway cars, and is especially designed as an improvement upon or addition to the front covered by my application for United States Letters Patent, Serial No. 205,813, filed April 30, 1904, and allowed June 6, 1904.

In the application referred to the construction described and claimed does not protect the operative of the car at the sides of the platform, but merely directly in front thereof. Consequently when a storm is prevailing the operative is exposed to the elements at the sides, and as the car is not always advancing into the face of the storm such exposure admits the elements to the platform from the sides thereof.

It is therefore the object of the present invention to provide simple and efficient means of a portable nature whereby when the main curtain of the storm-front is placed in operative position the sides of the platform will be closed and the operative effectually protected at such points, as well as at the spaces at the sides of the main curtain formed by the distension thereof.

With this general object in view and others, which will appear as the nature of the improvements is better understood, the invention consists, substantially, in the novel construction, combination, and arrangement of parts, as will be hereinafter fully described, illustrated in the accompanying drawings, and pointed out in the appended claims.

In the drawings, Figure 1 is a side elevation of one end of a car equipped with a storm-front constructed in accordance with my former invention and embodying the herein-described improvement. Fig. 2 is a transverse sectional view thereof, taken through the dis-

tenders, the side curtains being applied in their extended position. Fig. 3 is a similar view of one side of the car with the rear side curtain extended. Fig. 4 is a detail perspective view, on an enlarged scale, of a portion of one of the front side curtains to disclose more clearly the construction of attaching-hooks. Fig. 5 is a side elevation of another form of curtain.

Referring to the drawings, the numeral 1 designates the platform of a car; 2, the dashboard thereof; 3, the overhanging car-hood, and 4 the vertical supporting-rods extending from the platform to the hood. These are all of usual construction; but in addition thereto the numeral 5 designates the upper distender, 65 and 6 designates the lower distender, whereby the main curtain 7 of the storm-front is projected in advance of the dashboard to permit ready manipulation of the brake-handle and current-controller of the car. These parts are 70 all in accordance with the invention covered by my previous application hereinbefore referred to, and therefore require no detailed explanation herein.

As before premised, it is the object of the present invention to protect the operative of the car at the sides of the platform, which was not contemplated by the construction covered by my former application, and to the accomplishment of this end front side curtains 8 are 80 employed, which curtains are applied to the distenders in order to close the spaces formed between the edges of the main curtain 7 and the supporting-bars 4. Each of these curtains 8 is formed of suitable material and is also 85 provided with a sight-opening covered by a sheet of transparent material 9, such as celluloid, mica, and similar substances capable of flexion. The curtains 8 are held in position through the medium of spring attaching-hooks 90 10, said hooks being located at the upper and lower ends of said curtains and each provided with a coil 11, so that said hooks may be tensioned, and when the curtains are applied the hooks are connected to the upper and lower 95 distenders 5 and 6, as clearly shown, but whereby they may be readily removed when necessity for use of the storm-front does not prevail.

When applied in the manner indicated, the 100

curtains 8 effectually close the spaces at the points immediately adjacent to the side edges of the main curtain, and the contiguous edges may be fastened together through the medium of buttons, straps, or other suitable fastening devices to effect a closure therebetween.

To close the sides of the platform, a rear side curtain 12 is suspended from each side of the hood 3, the curtain being connected to a suitable spring-roller 13, suspended in any suitable form of journals, and when each of said curtains is extended the same is held in such position through the medium of fastening devices 14, connected to the lower end of each curtain and coacting with eyes 15, which latter are secured at different points between the top of the dashboard and the step. This arrangement of eyes 15 enables the lower end of the curtain to be fastened at different points, thus enabling the space to be either entirely closed or only partially so, in accordance with the desires of the car operative.

In lieu of the form of front side curtains illustrated in Figs. 1 to 4 that form illustrated in Fig. 5 may be substituted, and it will be noted that in this figure is disclosed a spring-roller 16 which is connected to the upper end of the curtain, which roller will be suspended from the upper distender 5 through the medium of hooks 17, detachably connected to said distender. The lower end of the curtain is also provided with attaching-hooks 10 for engagement with the lower distender to hold the curtain in its extended position and in a manner which is obvious. This curtain is also provided with a sight-opening covered by a transparent medium, as shown at 18.

Having thus described the invention, what is claimed as new, and desired to be secured by Letters Patent, is—

1. In a portable storm-front, the combination with a main curtain, an upper distender adapted to be connected to the hood of the car, and a lower distender adapted to be connected to the dashboard of the car, of forward side curtains arranged between said upper and lower distenders and detachably connected thereto for closing the spaces formed

at the sides of the main curtain by the distension thereof.

50

2. In a portable storm-front, the combination with a main curtain, an upper distender adapted to be connected to the hood of the car, and a lower distender adapted to be connected to the dashboard of the car, of forward side curtains arranged between said upper and lower distenders and detachably connected thereto for closing the spaces formed at the sides of the main curtain by the distension thereof, and rear side curtains arranged beneath the hood of the car and adapted to close the spaces at the sides of the car-platform.

55

3. In a portable storm-front, the combination with a main curtain, an upper distender adapted to be connected to the hood of the car, and a lower distender adapted to be connected to the dashboard of the car, of forward side curtains arranged between said upper and lower distenders and detachably connected thereto for closing the spaces formed at the sides of the main curtain by the distension thereof, and fastening devices for connecting the contiguous edges of the main curtain and the forward side curtains.

75

4. In a portable storm-front, the combination with a main curtain, an upper distender adapted to be connected to the hood of the car, and a lower distender adapted to be connected to the dashboard of the car, of forward side curtains arranged between said upper and lower distenders and detachably connected thereto for closing the spaces formed at the sides of the main curtain by the distension thereof, rear side curtains arranged beneath the hood of the car and adapted to close the spaces at the sides of the car-platform, and fastening devices for connecting the contiguous edges of the main curtain and the forward side curtains.

80

In testimony whereof I affix my signature in the presence of two witnesses.

HUGH M. ADAMS.
